UNITED STATES PATENT OFFICE

109,205

DESIGN FOR A TRANSPARENT COSMETIC COMPACT

Arthur R. Botham, New York, N. Y.

Application December 14, 1937, Serial No. 73,610

Term of patent 14 years

To all whom it may concern:

Be it known that I, Arthur R. Botham, a citizen of the United States, residing in the city and State of New York, have invented a new, original, and ornamental Design for a Transparent Cosmetic Compact, of which the following is a specification, reference being had to the accompanying drawing, forming a part thereof:

Fig. 1 is a perspective view of a transparent cosmetic compact in open position showing my new design;

Fig. 2 is a side elevational view thereof in closed position showing a portion of the same broken away; and

Fig. 3 is an end view thereof.

I claim:

The ornamental design for a transparent cosmetic compact, substantially as shown and described.

ARTHUR R. BOTHAM.
